DEEP-WELL FLUID-ACTUATED PUMP

Application filed May 24, 1930. Serial No. 455,221.

This invention relates to a hydraulically operated deep well pump, wherein the motive power may be transmitted to the fluid lifting plunger from a hydraulic piston at or near the surface of the well hole. The present invention contemplates overcoming the disadvantages resultant from using a long sucker rod string which is subject to stretching and flexing with consequent wear and lag of the stroke of the fluid lifting plunger in relation to the power strokes applied at the upper end of the string. In accordance with my invention, a closed hydraulic system is employed and the actuating fluid is oscillated. Since such actuating fluid lines are long and the passageway walls are of resilient metal which may have stretched making the passage an expansible chamber, I have also provided auxiliary means to compensate for any such expansion due either to the expansion of the actuating fluid chamber elements or the actuating fluid itself.

The present invention has for its objects the provision of an efficient structure with the pump motor, and fluid lifting pump insertable and movable from the well hole as a unit and having any or all of the features before mentioned.

An embodiment of my invention is illustrated in the accompanying drawings, in which:

Fig. 1 is a section through a well hole with parts broken out to make the view compact and showing an installation of my structure partly in section; Fig. 2 is a longitudinal section on an enlarged scale of the pump operating head; Fig. 3 is a longitudinal section through the hydraulic motor assembly; Fig. 4 is a longitudinal section through the lifting pump assembly; Fig. 5 is a section as seen on the line 5-5 of Fig. 3; and Fig. 6 is a section as seen on the line 6-6 of Fig. 4.

Referring more particularly to Fig. 1 a well hole is shown lined with a well casing 10 such as commonly employed and consisting of sections coupled together by collars, there being a shoe 11 adjacent the lower end having a tapered bore to form a seat for the oil and pump string of tubing. This string is indicated generally by 12 in Fig. 1. A

short sucker rod string is indicated by 13 and is reciprocated by an engine 14 of any suitable type. Communicating with the oil string 12 and operated by the engine 14 is a compensating booster 15.

The oil string comprises a line of inner tubing 16 and a line of outer tubing 17, both closed at the top by a head 18. However, the portion of the head above the inner tubing has vents 19. Pipe 20 is connected to the head 18 and serves for the discharge of oil or actuated fluid being pumped. A transfer head 21 is mounted in the oil and hydraulic string. This transfer head is divided with passages 22 and 23 which places the bore of the inner string in communication with the annular space between the outer and inner tubing. The arrangement is such that the annular space between tubings 16 and 17 above the transfer head is connected with the bore of the inner tubing 16 below the transfer head and the bore of the inner tubing 16 above the transfer head is connected to the annular space below the transfer head. A piston rod 25 is connected to the sucker rod string 13 and has at its lower end a solid piston 26 disposed to coat with the inner tubing and form an actuating fluid pump.

Connected to the upper end of the sucker rod string is an engine piston rod 27 having a bore extending partially therethrough. A standard 28 supports a cylinder 29 within which is an engine piston 30 secured to the piston rod 27. On the upper head of the engine cylinder is a valve casing 31 housing a piston pilot valve 32. Secured to and depending from the piston valve 32 is a valve rod 33 having a head 34 disposed within the bore of the engine piston rod and arranged to be moved at the ends of the engine piston stroke. Connected to the valve casing 31 is a pipe line 35 for fluid under pressure and spaced therefrom is a pipe line 36 serving as an exhaust. Connected to the casing 31 longitudinally intermediate the pipes 35 and 36 is a pipe line 37 communicating with one end of a main valve casing 38 on the end cylinder. The bore of main casing 38 is reduced at one end as indicated by 39. Connected to the valve casing 38 adjacent the

ends are exhaust pipes 40 and 41. Intermediate the exhaust pipes is an intake pipe 42. A motive fluid port 43 connects the bore of the main valve casing and one end of the engine cylinder through a series of openings 43a arranged in a line and at an angle to the axis of the cylinder. A motive fluid port 44 is disposed at the opposite end of the main valve casing and in communication with the engine cylinder bore at the other end. Disposed within the bore of the main valve casing are valve pistons 45 and 46 and in the reduced portion of the bore is a valve piston 47. Pistons 45, 46, and 47, are mounted upon a valve rod 48. The engine just described except for the valve stem 48 is a type of engine well known in the art the details thereof of form no part of the present invention except for the valve stem 48 and the openings 43a. At the lower end of the engine piston travel, the pilot valve stem 33 is engaged to move the pilot valve 32 to the position shown in Fig. 2. In this position the pressure fluid passes from pipe 35 through the valve to pipe 37 and thence acts against the piston 45 to move the main piston to the position shown in Fig. 2. At the reverse or upper end of the stroke, the pilot valve 32 is moved to the upper end of its valve casing connecting pipe 37 with exhaust pipe 36. The motive fluid will enter the main valve casing 38 and act upon the piston 46 to move the latter to its upper position, thereby connecting port 44 with the exhaust and port 43 with the intake. As the piston 30 approaches the upper end of its stroke, it gradually closes the openings 43a so as to check the travel of piston 30. Reciprocation of the sucker rod string is thus caused, and this causes reciprocation of the solid piston 26 in its barrel formed by a portion of the string of tubing 16. An actuating fluid is confined in the actuating fluid line below piston 26 and will be oscillated by reciprocation of the piston 26.

Referring to Figs. 4, 5, and 6, a barrel is secured to the lower end of the outer string of tubing 17. This barrel is marked 49 and has an intermediate head 50 provided with a suitable packing to permit the reciprocation of a hollow piston rod. The upper end of barrel 49 constitutes a motor cylinder and the lower end of the barrel a lifting fluid pump. The upper end of the barrel 49 is provided with a threaded boss 51 to which the tubing string is connected. Thus, the lower portion of the bore of fluid string 16 connects directly with the bore of barrel 49. At the side of the barrel 49 is a longitudinally extending enlargement having a passageway 52 communicating with the bore of the motor cylinder above head 50. The lower portion of barrel 49 has a shoe formed thereon and marked 53. This shoe is tapered and adapted to seat in seat 11. A valve port extends through the shoe for placing the lower portion of the

casing 10 in communication with the bore of the lifting pump cylinder and mounted there-in are the elements of a standing valve marked generally by 54. A lifting pump piston 55 is mounted to be reciprocated in the lifting pump cylinder and has a valve portion over which is mounted a hollow piston rod 56 connected to the motor piston 57 mounted for reciprocation in the motor cylinder. Thus, the pistons are floated in the barrel 49, the piston 65 being a valve piston and the motor piston being a solid piston. An actuated fluid, preferably a liquid is confined in the tubing 16 between the actuating fluid piston 26, the transfer head, the passage 23, the annular space between the outer tubing 17 and the inner tubing 16 below the transfer head, passage 52 and the motor cylinder of the valve 49 between the motor piston 57 and the head 50. Upon reciprocation of the piston 26, the column of actuated fluid will be oscillated and the motor piston 57 reciprocated in correspondence with the piston 26. This causes the lifting fluid piston 55 to be reciprocated and results in lifting of the actuated fluid, it passing through the hollow piston rod 56 into the space of the motor cylinder above the motor piston 57, thence upwardly through the inner tubing 16 to the transfer head 21 and by way of passage 22 to the annular space between the outer tubing 17 and the inner tubing 16. It is discharged from the upper annular space through discharge pipe 20.

In long string of tubing, there may be some expansion and contraction. Furthermore, in oil wells, there is usually gas in the liquid, and this gas would expand and contract. In order to counteract this expansion and contraction effect, I have provided a compensating booster to follow the actuated pump piston or lifting piston on its down stroke and to thus maintain constant the volume of the column of fluid against the tendency to expand on the downstroke both due to its own elastic qualities and that of the tubing in which it is confined. To this end, I have provided adjacent the engine a compensator cylinder 58 communicating at one end with the discharge pipe 20. In the cylinder 58 is a solid piston 59. The piston rod of the compensator piston 59 is connected by a linkage indicated generally by 60 to the engine piston rod 27. The linkage is such that on the down stroke of the engine piston, there will be an in stroke of the piston 59. The amount of displacement of the compensator piston should be designed in accordance with the elastic characteristics of the fluid being lifted and also the elasticity of the tubing. Although in the present instance, I have shown the compensating piston following the actuating fluid piston, to have an effective inverse stroke, it will be understood that if there is a lag of the fluid being lifted as compared

with the actuating fluid piston, suitable linkage may be provided so that the compensating piston follows the lifting fluid, in its descent. The discharge of lifting fluid will be on the up stroke and on the down stroke the discharge line should be closed. To this end, I have incorporated in the compensator a valve casing 61 and a valve 62 connected to valve stem 48 to control a discharge port 63 which communicates with the ultimate discharge line 64. Thus, the discharge line will be open on the lifting stroke and closed on the return stroke of the lifting fluid piston and expansion and contraction of the fluid column with resultant ineffective pumping action are prevented.

What I claim is:—

1. A deep well pumping device comprising a string having an outer tubing and an inner tubing nested therein to provide fluid lines, said inner tubing including an actuating pump cylinder, a solid piston in said actuating pump cylinder, means to reciprocate said solid piston, a transfer device in said tubing having passages placing the outer fluid line below said transfer device in communication with the inner fluid line below said piston and the inner fluid line below said transfer device in communication with the outer fluid line above said transfer device; a pump cylinder forming a continuation of the outer tubing and in communication with the lower part of the inner tubing, an actuated fluid pump cylinder below said motor cylinder, a valved pump piston in said actuated fluid pump cylinder, a motor cylinder in said string, a motor piston in said motor cylinder, a hollow piston rod connecting said actuated pump piston and said motor piston, the outer fluid line below said transfer device communicating with said motor cylinder below the motor piston.

2. A deep well pumping device comprising an outer tubing and an inner tubing nested therein to provide fluid lines, said inner tubing including an actuating pump cylinder, a solid piston in said actuating pump cylinder, means to reciprocate said solid piston, a transfer head in said tubing having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the inner tubing, the lower end of said outer tubing having a seat for seating in said shoe, said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head communicating with said motor cylinder below the motor piston.

3. A deep well pumping device comprising an outer tubing and an inner tubing nested therein to provide an actuating fluid line and a flow line, said inner tubing including an actuating pump cylinder, a solid piston in said actuating pump cylinder, means to reciprocate said solid piston, a transfer head in said tubing having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the inner tubing, the lower end of said outer tubing having a seat for seating in said shoe, said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head communicating with said motor cylinder below the motor piston.

the outer fluid line below said transfer head communicating with said motor cylinder below the motor piston.

3. A deep well pumping device comprising an outer tubing and an inner tubing nested therein to provide fluid lines, said inner tubing including an actuating pump cylinder, a solid piston in said actuating pump cylinder, a sucker rod line connected to said solid piston, a transfer head extending across both tubing below said solid piston having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the inner tubing, said pump and motor cylinder being divided by an intermediate head into an actuated fluid pump cylinder and a motor cylinder, a valved pump piston in said actuated fluid pump cylinder, a motor piston floating in said motor cylinder, a hollow piston rod connecting said actuated pump piston and said motor piston, the outer fluid line below said transfer head communicating with said motor cylinder below the motor piston.

4. A deep well pumping unit for insertion in a well casing having a shoe comprising an outer tubing and an inner tubing nested therein to provide fluid lines, said inner tubing including an actuating pump cylinder, a solid piston in said actuating pump cylinder, means to reciprocate said solid piston, a transfer head in said tubing having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the inner tubing, the lower end of said outer tubing having a seat for seating in said shoe, said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head communicating with said motor cylinder below the motor piston.

5. A deep well pumping device comprising an outer tubing and an inner tubing nested therein to provide an actuating fluid line and a flow line, said inner tubing including an actuating pump cylinder, a solid piston in said actuating pump cylinder, means to reciprocate said solid piston, a transfer head in said tubing having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the inner tubing, the lower end of said outer tubing having a seat for seating in said shoe, said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head communicating with said motor cylinder below the motor piston.

ciprocate said solid piston and oscillate the actuating fluid, a transfer head in said tubing having passages placing the outer fluid line below said transfer head in communication 5 with the inner fluid line below said piston and the inner fluid line below said transfer head in communication with the outer fluid line above said transfer head; a pump and motor cylinder forming a continuation of the outer tubing and in communication with the lower part of the flow line provided by inner tubing, 10 said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head 15 communicating with said motor cylinder below the motor piston; and compensating means in said flow line to boost the descent of actuating fluid.

6. A deep well pumping device comprising an outer tubing and an inner tubing nested therein to provide an actuating fluid line and a flow line, said inner tubing including an actuating pump cylinder, a solid piston in said actuating pump cylinder, a sucker rod line connected to said solid piston, a transfer head extending across both tubing below said solid piston having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the flow line provided by inner tubing, 20 said pump and motor cylinder being divided by an intermediate head into an actuated fluid pump cylinder and a motor cylinder, a valved pump piston in said actuated fluid pump cylinder, a motor piston floating in said motor cylinder, a hollow piston rod connecting said actuated pump piston and said motor piston, the outer fluid line below said transfer head communicating with said motor cylinder below the motor piston; and compensating means in said flow line to boost the descent of actuating fluid.

7. A deep well pumping device comprising a string having an outer tubing and an inner tubing nested therein to provide an actuating fluid line and a flow line; said inner tubing including an actuating pump cylinder, a solid piston in said actuating pump cylinder, an operating head for reciprocating said solid piston and oscillating actuating fluid, a transfer device in said tubing having passages placing the outer fluid line below said transfer device 25 in communication with the inner fluid line

below said piston and the inner fluid line below said transfer device in communication with the outer fluid line above said transfer device; an actuated pump cylinder forming a continuation of the outer tubing and in communication with the lower part of the flow line provided by the inner tubing, an actuated fluid pump cylinder below said motor cylinder, a valved pump piston in said actuated fluid pump cylinder, a motor cylinder in said string, a motor piston in said motor cylinder, a hollow piston rod connecting said actuated pump piston and said motor piston, the outer fluid line below said transfer device communicating with said motor cylinder below the motor piston; a reciprocating expansible chamber connected in said flow line, means connecting said operating head and said expansible chamber pump to expand the chamber of said expansible pump on descent 30 of the actuating fluid.

8. A deep well pumping device comprising an outer tubing and an inner tubing nested therein to provide an actuating fluid line and a flow line, said inner tubing including an actuating pump cylinder, a solid piston in said actuating pump cylinder, an operating head for reciprocating said solid piston and oscillating an actuating fluid, a transfer head in said tubing having passages placing the outer fluid line below said transfer head in communication with the inner fluid line below said piston and the inner fluid line below said transfer head in communication with the outer fluid line above said transfer head; a pump and motor cylinder forming a continuation of the outer tubing and in communication with the lower part of the flow line provided by the inner tubing, 40 said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the outer fluid line below said transfer head communicating with said motor cylinder below the motor piston; a reciprocating expansible chamber connected in said flow line, and means connecting said operating head and said expansible chamber pump to expand the chamber of said expansible pump on descent of said actuating fluid.

9. A deep well pumping device comprising an outer tubing and an inner tubing nested therein to provide an actuating fluid line and a flow line, said inner tubing including an actuating pump cylinder, a solid piston in said actuating pump cylinder, an operating head having a sucker rod line connected to said solid piston, a transfer head extending across both tubing below said solid piston having passages placing the outer fluid line below said transfer head in communication 120

with the inner fluid line below said piston and the inner fluid line below said transfer head in communication with the outer fluid line above said transfer head; a pump and motor cylinder forming a continuation of the outer tubing and in communication with the lower part of the inner tubing, said pump and motor cylinder being divided by an intermediate head into an actuated fluid pump cylinder 10 and a motor cylinder, a valved pump piston in said actuated fluid pump cylinder, a motor piston floating in said motor cylinder, a hollow piston rod connecting said actuated pump piston and said motor piston, the outer fluid line below said transfer head communicating with said motor cylinder below the motor piston; a reciprocating expandable chamber connected in said flow line, means connecting said operating head and expandable chamber pump to expand the chamber of said expandable pump on descent of the actuating fluid.

10. A deep well pumping device comprising a string having an outer tubing and an inner tubing nested therein to provide an actuated fluid line and a flow line, said inner tubing including an actuating pump cylinder, a solid piston in said actuating pump cylinder, an operating head to reciprocate said solid piston; an actuated fluid pump cylinder forming a continuation of the outer tubing and in communication with the flow line, a motor cylinder in said string having its upper end communicating with said flow line, a valved pump piston in the actuated fluid pump cylinder, a motor piston in said motor cylinder, a hollow piston rod connecting said actuated pump piston and said motor piston, the actuated fluid line communicating with said motor cylinder below the motor piston; and compensating means in said actuated fluid line connected to said operating head to boost the descent of actuating fluid.

11. A deep well pumping device comprising a string having an outer tubing and an inner tubing nested therein to provide an actuated fluid line and a flow line; said inner tubing including an actuating pump cylinder, a solid piston in said actuating pump cylinder, means to reciprocate said solid piston, a pump and motor cylinder forming a continuation of the outer tubing and in communication at its upper end with the lower part of the flow line, said pump and motor cylinder being divided by an intermediate head into an actuated fluid pump cylinder and a motor cylinder, a valved pump piston in said actuated fluid pump cylinder, a motor piston in said motor cylinder, a hollow piston rod connecting said actuated pump piston and said motor piston, the actuated fluid line communicating with said motor cylinder below the motor piston.

12. A deep well pumping device comprising a string having an outer tubing and an inner tubing nested therein to provide an actuated fluid line and a flow line, said inner tubing including an actuating pump cylinder, a solid piston in said actuating pump cylinder, an operating head to reciprocate said solid piston; an actuated fluid pump cylinder forming a continuation of the outer tubing and in communication with the lower part of the flow line, a valved pump piston in said actuated fluid pump cylinder, a motor cylinder in said string, a motor piston in said motor cylinder, a hollow piston rod connecting said actuated pump piston and said motor piston, the actuated fluid line communicating with said motor cylinder below the motor piston; and an expandable chamber pump in said flow line connected to said head to boost the descent of actuating fluid.

13. A deep well pumping device comprising a string having an outer tubing and an inner tubing nested therein to provide an actuated fluid line and a flow line, said inner tubing including an actuating pump cylinder, a solid piston in said actuating pump cylinder, an operating head to reciprocate said solid piston; an actuated fluid pump cylinder forming a continuation of the outer tubing and in communication with the lower part of the flow line, a valved pump piston in said actuated fluid pump cylinder, a motor cylinder in said string, a motor piston in said motor cylinder, a hollow piston rod connecting said actuated pump piston and said motor piston, the actuated fluid line communicating with said motor cylinder below the motor piston; and an expandable chamber pump in said flow line connected to said head to boost the descent of actuating fluid.

In witness that I claim the foregoing I have hereunto subscribed my name this 7th day of May, 1930.

PAUL H. GRANGER.
